UNITED STATES PATENT OFFICE.

FRANCIS KINGSLEY, OF PELHAM MANOR, NEW YORK.

GUARD FOR SHOE-BLACKING STANDS.

Application filed January 5, 1922. Serial No. 527,173.

To all whom it may concern:

Be it known that I, FRANCIS KINGSLEY, a citizen of the United States, residing at Pelham Manor, Westchester County, in the 5 State of New York, have invented certain new and useful Improvements in a Guard for Shoe-Blackening Stands, of which the following is a specification, reference being had to the accompanying drawing, forming a 10 part hereof.

In the polishing of shoes by mechanical devices, as opposed to hand-polishing means, it has been found that dust and polish are apt to be thrown from the surface of the 15 shoe for a considerable distance, thereby spattering bystanders and patrons. Where such mechanical shoe polishing machines are arranged with a bank of seats, as is often the case, the dust and polish are apt to be 20 thrown from one foot rest to another, thereby interfering mutually with proper cleansing and polishing of the shoes of the patrons. In either case, not only is the action annoying and, perhaps, detrimental to business, since it discourages bystanders, but it 25 may also result in some injury to clothing. The principal object of the present invention is to provide a curtain or shield of simple construction, which may be moved 30 readily by the operator into position after the feet of the patron are placed on the foot rests, to prevent dust and polish from being thrown out on one or more sides. A further object of the invention is to provide a 35 curtain or shield for the purpose indicated which is supported in convenient relation to the foot rests and to the operator whereby it may be removed quickly into or out of 40 protecting relation to the shoes, so as not to interfere with the convenient movement of the feet on to the rests and away from them. This phase of the invention is important 45 since mechanical shoe polishing devices are designed primarily to facilitate the polishing operation and reduce the amount of time involved. While the invention is not to be limited to the details of construction of the illustrated embodiment, one suitable curtain is shown conventionally in the drawing, wherein—

Figure 1 is a view partly in side elevation and partly in vertical section of a mechanical shoe polishing stand showing the improved curtain in nonprotecting position 55 with relation to the foot rests.

Figure 2 is a similar view but showing the curtain in protecting position.

Figure 3 is a detail view in perspective and on a somewhat larger scale showing the parts in the relation indicated in Figure 1. 60

The invention is not to be limited to any of the details of construction relating to the main frame of the stand, although for convenience such frame may be made up of piping *a* on which are supported two foot 65 rests *b* to receive the feet of the patron in convenient relation for treatment with the mechanical polishing machine. The operator may be seated on a stool *c*, while the patron is in a relatively elevated position on 70 a stool *d*. It has been found that, having such a general relation of parts as described, a mechanical polisher will throw dust or polish from the shoes for a distance of two or three feet, much to the annoyance of 75 prospective patrons or bystanders who may be near the stool *d*. Further, a similar spray may be thrown to the right and left and reach the shoes or clothing of a patron at the next foot rest. This dust and polish 80 may spoil the shine at the next stand and injure the clothing of all whom it reaches. It is this condition of affairs which the present invention seeks to remove. Broadly, the invention consists in providing a curtain or 85 shield which may be movable readily by the operator into such relation to the shoes of the patron, after they are placed on the foot rests, as to confine the dust and polish spray on one or more sides. The improved curtain 90 or shield furthermore, is of simple construction and is disposed within easy reach of the operator so as not to cause any loss of time in moving the curtain into and out of protecting relation to the shoes when they are 95 to be placed on the foot rests or removed therefrom. The invention is not to be limited to the particular form or mounting of the improved curtain, although the embodiment illustrated is of simple and convenient 100 construction and may be adapted to the intended purpose. As shown, the piping *a* may include two vertical sections *a'* at opposite sides of the foot rests and on the vertical sections may be pivoted, as at *e*, a 105 three-sided frame consisting of a front portion *f* and two side shields *f'*. A shield affording protection at three sides of the foot rests will usually be desired and for that reason the illustrated embodiment is so 110

shown. The front side f is of narrow width so as to afford ample clearance on the foot rests b when the shield is thrown up into inoperative position (Figures 1 and 3), but may have hinged thereto a lower section f^2 which will hang vertically and afford ample protection when the shield is removed into protecting position (Figure 2).

When the patron takes his place on the stool and places his feet on the foot rests b , he will find the side plates f' in vertical position with the front section f well below the foot rests so as not to interfere with the placing of the feet thereon. The operator on the stool c will grasp one or both of the side plates f' and swing them downwardly into horizontal position about the pivots e thereby throwing the front section f with its hinged section f^2 into vertical position behind the feet. The upper edge of the side plates f' as well as the front section f will be well above the shoes so that dust and spray thrown out therefrom will be intercepted and protection will be afforded on all sides of the shoes except, perhaps, on the operator's side. Protection for the operator can also be afforded in accordance with the proposal of the present invention, without departing from it. The movement of the curtain into protecting relation to the shoes is accomplished quickly and conveniently. When the polishing operation has been completed, the operator may with equal

convenience and dispatch throw the shields f' upward so as to move the front section f 35 from the path which the feet will take when being removed from the rests.

I claim as my invention:

1. A guard for shoe blacking stands provided with footrests, comprising a shield 40 having portions disposed in planes on opposite sides of the footrests, and a portion connecting said first mentioned portions, and means supporting said shield for movement from a position wherein the connecting 45 portion thereof is disposed behind the heels, to a position wherein it is disposed below the footrests.

2. A guard for shoe blacking stands comprising a three-sided curtain supported pivotally on its sides and in such relation to the foot rests as to be swung up or down about its pivots into and out of protective relation to the shoes on the foot rests. 50

3. A guard for shoe blacking stands comprising a main frame for the stand including two upright sections disposed at opposite sides of the foot rests; a stiff frame having two side plates pivoted on said uprights and a front section, an additional section 55 hinged to said front section and adapted to hang in line therewith when the curtain is in operative relation to the foot rests. 60

This specification signed this 4th day of January, A. D. 1922.

FRANCIS KINGSLEY.
